UNITED STATES PATENT OFFICE

2,602,464

DOUBLE FLOAT-VALVE DEVICE

Standlee Greening, Norwalk, Calif., assignor to
 Agro Phosphate Company, a corporation of
 California

Application November 18, 1949, Serial No. 128,143

6 Claims. (Cl. 137—391)

1

This invention relates to a pressure control double float valve created expressly for liquids which may contain solid or semi-solid aggregates or matter in suspension that is apt to accumulate at valve stems and seats and thus render the valve inoperative. In colloidal mixtures such as fertilizers, and/or soil conditioners, such as phosphoric acid for instance, the suspended particles seem to have an attraction for valve seats and form a liquid barrier and this barrier must be dispersed. Reciprocation of a tapered valve head is generally sufficient to scatter the particles and reestablish normal flow in accordance to the valve setting. Ordinary valves become inoperative and require expensive watching and cleaning operations, but the valve means of this invention is automatically cleaned and freed of all obstructions and remains in constant and regular service.

One of the principal objects of this invention is to present a new and novel valve combination arrangement for constant pressure feed of viscous and non-viscous liquids which may contain lumpy material or colloidal material which is apt to collect around valve seats.

Another object is the production of a means of the kind described that is simple and durable in operation, dependable for constant carefree operation, convenient for installation, inexpensive, compact, efficient, and pleasing and attractive in appearances and satisfactory for use wherever found applicable.

Other objects, advantages and features of this invention will appear from a careful perusal of the accompanying drawings, the subjoined detailed description, the preamble of these specifications, and the appended claims.

Below, applicant describes one of the preferable forms of his invention in order to teach the art thereof and show how to make and use the same, but it is to be understood that the drawings and description thereof are not to limit the invention in any sense whatsoever except as the same is limited by the prior art. Language employed herein is not to be construed as giving any unauthorized person or organization the right to make, use and/or sell the invention herein disclosed.

In the drawings:

Figure 1 is a side elevational view with portions broken away to show details of the device,

Figure 2 is a bottom plan of the device,

Figure 3 is a top plan thereof,

Figure 4 is an enlarged bottom portion of the device shown in elevational view,

2

Figure 5 is an elevational view of a tank with the device of this invention attached thereto.

The particular form of the invention as illustrated, comprises the outer shell or cylindrical casing 1 having its lower end open and its upper end closed by the integral head 2; this head having the integral upright protrusion 3. An inlet bore or passage 4 is provided through the head which is designed to pass liquid into the large cylindrical chamber 5. This head 2 may be, if desired, a separate unit adapted to be cemented to the inner wall of the cylinder 1. The bore 4 has the offset portion 6 to provide an annular shoulder or valve seat and the under surface of the wall 7 about the bore 4 is smooth in order to provide another valve seat.

The open end of the cylinder is provided with the piston-like plug 8 which has the integral and downwardly directed connector or protrusion 9; the entire plug having a bore or passage 10, the top wall 11 of which is smooth to provide a valve seat 12 about the top of the bore. This plug has the threaded portion 13 which consists of a spiral groove which rides on a single short king thread member 14 that consists of a pin that slides into the cylinder through a pair of spaced apart aligned holes 15 and 16; this allows the pin to engage the groove.

Within the chamber 5 of the cylinder there are the pair of spaced float elements 17 and 18. The bottom float element having the centrally positioned sealed-in tube 19 which functions as a guide member for the valve stem 20, the top of this stem being screwed into or otherwise fixed to the bottom of float element 17 and the bottom end of the stem being fixed to the tapered valve head 21, as shown. Thus, the vertical movement of the top float will move the valve 21. This valve has an annular groove that accommodates the O ring 22.

The top float element 17 has a pair of spaced apart sealed-in tubes 23 and 24 which accommodate the valve stems or rods 25 and 26 respectively. These rods are screwed into or otherwise fixed to the top portions of the bottom float element 18 and the top ends of these rods are cemented to or otherwise fixed to a disc-like yoke member 27 which limits movement of the tapered valve head 28 which has a bore therein to accommodate a sliding short valve stem 29 that has its bottom end screwed into or otherwise fixed to the top float 17 at 29'. This short stem also slides through a bore in the center of the disc-like member 27 and has fixed to the top thereof another valve head 30 which is also tapered and

which is called the prime valve or prime regulating control valve. An annular groove accommodates the O ring 31 and another annular groove accommodates the upper O ring 32 in their respective valve heads. These O rings may be rubber or any other suitable material such as the well known "neoprene." Vertical movement of the bottom float 18 will move the valve head 28, but the top float will move the bottom valve and the very top valve.

Figure 5 shows the control valve device, indicated as 1' and, as attached to a tank 35 by means of a bracket 36 which has a cylindrical portion 37 that holds the control device 1'. This portion may be of thin metal and bolted at its openable portion 38, the outer wall of the device may have a peripheral recessed portion to accommodate the bracket portion 37. The top of the device is shown attached to the valve 39 by means of a hose that slides over the protrusion 3 and over a portion of the end of valve 39, and the bottom protrusion portion 9 of the device accommodates a pipe or hose 40 which conducts, for instance, phosphoric acid in measured amounts into the trough or irrigation ditch 41. The amount of acid fed to the ditch depends upon the setting of the plug 8 with respect to the hole or opening 34. A plurality of divisional lines are shown on the plug at 33 and these division lines are spaced at predetermined positions and numbered to indicate rate of liquid flow from the chamber 5, for instance, in pounds of acid per hour. The hole 34 is in the cylinder 1 and note that the zero line crosses the hole when the plug is set for complete closure of the valves 30 and 21.

Any suitable material may be employed for all the parts shown and described, but it has been found that clear plastics can be used so that the operator can see at a glance just what is happening inside the device.

Operation

As shown in Figure 1 of the drawings, the top valve 30 is closed tight because of the position of the plug 8, thus no liquid can enter into the chamber 5 via the ingress bore or passage 4. Also, no liquid can egress through bore 10 from the chamber 5 because of the tightly closed valve 21, that is, if some liquid were allowed to remain in the chamber 5. By rotating the plug 8 counterclockwise until the proper desired divisional line 33 on the plug is centered in the hole 34 of the cylinder, a certain predetermined amount or rate of flow of liquid is permitted through the bore 4, the lower valve 21 remaining closed until the upper float element 17 is raised by the liquid collected in the chamber 5. Until the lower float element is raised, the valve 28 remains open. The liquid, viscous or non-viscous, rises in the chamber 5 until the upper float element is affected and rises, then the outlet valve 21 is opened and a steady discharge is made at the rate set. The two floats are so balanced that valves 21 and 28 remain open as long as the valves are clear and unobstructed. The balance between the two floats and their valves times the distance between the valve seats creates static flow which by all laws of nature tend to remain in balance and there-fore static. The valve 30 is normally unaffected as this valve is controlled principally by the plug setting at the bottom of the device, but will be closed by the top float in certain cases. Note, that the discharge at 21 is practically at atmospheric pressure because of the vent hole v provided at the top of the chamber, thus a posi-

tive pressure or head pressure in the tank 35 is non-effective upon any part of the device except the very top valve.

Should the opening about the valve 21 become clogged for any reason, the liquid level in chamber 5 would rise until the upper float in conjunction with the lower float opens the valve 21 wide enough to let the interfering solids pass. However, when the valve 28 is closed, there is a trickle of liquid between the bore of the valve head 28 and the stem 29, there being sufficient loose play, until the bottom float completely closes the very top inlet valve 30 and this occurs before the liquid reaches the vent opening v. Normally, however, the obstruction about the outlet opening of valve 21 will pass through and not make it necessary to close the top valve 30. Should the upper valve 28 become clogged, then the chamber would soon be drained so as to let the lower float element fall and thus open the valve 28 wide enough to let the solids pass which have been blocking the way. The O ring 8' allows the plug 8 to be freely rotated by hand and prevents leakage.

It is believed that the above explanation makes it clear how the control device operates without any attendant. Such valve control means can remain in service for a long time and perform perfectly to the full satisfaction of rancher and farmer.

It is understood that various changes and modifications may be made in parts and details of form, style, design, and in construction of the whole or any part of the specifically described embodiment of this invention without departing from the spirit thereof in that such changes are considered as being within the scope of the following claims:

1. In a float valve device comprising a vertical casing with a float chamber therein, a pair of independently operative and tandem arranged floats in the chamber, an inlet valve at the top end of the chamber and an outlet valve at the bottom end of the chamber in combination with a closure for the bottom end of the casing, rigid means connecting the bottom float with the inlet valve for opening and closing it, rigid means connecting the top float with the outlet valve for opening and closing it, rigid means extending upwardly from the top float with a valve head thereon and an ingress opening at the very top of the casing with a valve seat to receive the valve head, means in combination with the closure to allow it to be adjusted vertically and hence regulate the position of the valve head through the outlet valve, and a vent at the top of the chamber.

2. The float valve device recited in claim 1 wherein the closure is provided with a spiral groove around its periphery, and a pin passing through a portion of the casing and into a portion of the groove to provide a threaded connection between the bottom of the casing and the closure.

3. In a regulatory valve device that has self-freeing valve openings from aggregates and the like; the device comprising an elongated vertical casing with an elongated vertically arranged chamber therein for passage of liquids, an ingress bore at the top end of the casing having top and bottom spaced apart valve seats and an adjustable closure means at the bottom end of the casing having an egress bore with a valve seat, a top float and a bottom float in the chamber, the top float having stem means fixed thereto and

freely passing through the bottom float and having a long tapered valve head fixed to its bottom end which is adapted to engage the valve seat of the egress bore, the bottom float having stem means fixed thereto which pass freely through the top float and which latter means has a tapered valve head fixed to the top thereof for making contact with the bottom valve seat of the ingress bore, and a valve stem fixed to the top of the top float and which is provided with a valve head at the top end thereof that is adapted to be adjusted with respect to the top valve seat in the ingress bore so that when the closure means is adjusted vertically, the latter mentioned valve head is adjusted through concerted movement of the valve head in the egress bore and the movement of the top float.

4. The float valve device recited in claim 3 wherein the closure means is provided with a spiral groove around its periphery, and a pin passing through a portion of the casing and into a portion of the groove to provide a threaded connection between the bottom of the casing and the closure means.

5. In a float valve device comprising a casing with a chamber having an inlet valve at the top and an outlet valve at the bottom thereof, a pair of floats in the chamber between the valves, one of the floats having connection with the outlet valve and the other connection with the inlet valve, said floats operating in a manner that an increased level of liquid in the chamber tends to close the inlet valve and open the outlet valve wider, and a decrease in level tends to close the outlet valve and open the inlet valve wider, a prime control valve at the very top of the casing for the purpose of setting the rate of flow, a vent at the top of the chamber, means making a rigid connection between the control and outlet valves, the outlet valve having threads mesh with means at the bottom of the casing so that the outlet valve can be manually adjusted along with

the prime control valve for limiting the liquid flow through the chamber.

6. In a float valve device for regulating the flow of liquids which may contain agglomerations, the device comprising a casing with an elongated chamber therein that has an inlet valve at the top thereof and an outlet valve at the bottom thereof, a pair of floats in the chamber between the above mentioned valves, one of the floats in the chamber having connection with the outlet valve and the other float having connection with the inlet valve, said mentioned floats operating in a manner that an increased level of liquid in the chamber operates the inlet valve toward closing position and operates the outlet valve wider, and a decrease in level of the liquid operates the outlet valve toward closing position and the inlet valve to a wider open position, a prime control valve at the top of the casing above the inlet valve and which control valve is for the purpose of setting the flow of liquid through the chamber at a definite rate, an air vent at the very top of the chamber, means joining the control valve and the outlet valve together for joint operation, and means for adjusting the position of the outlet valve.
